COLD PROCESS FOR PRODUCING AN
IMPROVED SOAP COMPOSITION

Roy W. Peterson, Fresno, Calif.

Application March 8, 1949, Serial No. 80,154

4 Claims. (Cl. 252—132)

1
The present invention relates to an improved soap and a cold-made process for producing the same.

Soaps are generally produced by one of three well known processes generally referred to as the full-boiled process, the half-boiled process, and the cold-made process. Each of these processes have their individual advantages and disadvantages. Explanation of the present invention is facilitated by comparison with well known process of soap production.

The full-boiled process is the one most generally employed in soap making and consists of a series of steps including several brine changes, a so-called "strong" change, and a finishing change. Successive steps of boiling are required. Although the reaction that goes on in saponification is exothermic, much steam or other source of heat is required to raise and to maintain requisite temperatures. The process not only requires considerable heat and thus objectionable fuel expense, but also demands complex equipment and apparatus. The temperatures required in forming the soap make the selection of apparatus materials of importance in avoiding soap discoloration. The full-boiled process requires a period of time, usually several days, to produce a batch of soap. The advantages of this process are that scraps of soap can be reworked and processed, glycerin can be extracted from the soap, and soaps of various qualities can readily be formed and segregated.

The half-boiled process is more economical than the full-boiled process but is productive of inferior soaps and precludes the extraction of glycerin.

The simplest method of making soap is the cold-made process. It is distinguished from the half-boiled process largely in the matter of temperature. This process, however, requires precise controls. The fats must be purer, the lye of exactly the correct proportion and concentration, and the temperature controls precise. None of the glycerin is recovered in this process, all scrap soap must be discarded for no provision is made for reworking the same, and incomplete saponification frequently results in discolored or other defective soap batches. Further, it is difficult to add additional ingredients such as perfume or the like to soap made by the cold-made process because of its susceptibility to the breaking of the emulsion during saponification incident to the introduction of such additional materials and even the most careful stirring. Soap produced by the cold-made process normally must age

months before it is sufficiently cured for the market.

An object of the present invention is to provide an improved process for making soap.

5 Another object is to provide a soap making process that obviates previous requirements for expensive, elaborate, and complex apparatus and makes possible the production of high quality soap by small producers with limited capital.

10 Another object is to provide a simple process for soap making adapted to produce high quality soap having the characteristics of aged soap in a much shorter period than heretofore possible.

15 Another object is to provide a process for soap making of the so-called cold-made type obviating the precise temperature, proportion and concentration requirements heretofore demanded in such a process.

20 Another object is to provide a cold-made process for making soap that eliminates the waste, occasional soap discoloration and incomplete saponification characteristic of the conventional cold-made processes.

25 Another object is to provide for the convenient introduction of perfumes and/or filling materials in a soap produced by a cold-made process.

Another object is to provide a bar soap of improved physical form conducive to washing efficiency and a method of forming the same economically.

30 Another object is to provide a soap having improved sudsing and cleansing characteristics.

Another object is to provide a soap having the characteristics of aged soap soon after its formation.

35 A further object is to provide a soap that has efficient cleansing properties and yet is mild and gentle to the skin, delicate fabrics, hair, painted surfaces, linoleum, asphalt tile, and other materials on which conventional soaps have a deleterious effect.

40 Still further objects and advantages will become apparent in the subsequent description in the specification.

45 Referring to the drawing:

Fig. 1 is a schematic representation, or flow diagram, illustrative of the soap making process of the present invention.

50 Fig. 2 is a greatly enlarged schematic representation of the soap structure of the present invention productive of certain advantages subsequently described.

Referring in greater detail to the drawing:
In Fig. 1, the numeral 10 designates oleaginous

material suitable for making soap of the present invention. Coffee oil, soybean oil, coconut oil, peanut oil, rice oil, animal fat, and any suitable fatty acid may be employed. A source of dilute solutions of water soluble organic acids is represented at 11. Acetic acid, oxalic acid, citric acid, tartaric acid and many others are suitable to the purpose. The acids are preferably diluted with water, as will subsequently become apparent in the examples, to form weakly aciduous solutions. The fatty acid and the organic acid solutions are mixed, as indicated at 12, to form a fatty acid and a water soluble acid emulsion.

A source of dilute acetic acid is indicated at 15. The acetic acid is conveniently of approximately five percent (5%) strength in water, such as is found in vinegar. A source of alkali metal, such as sodium hydroxide in commercial lye form, is represented at 16. The acetic acid solution and the sodium hydroxide are agitated at 17 until the lye dissolves in the acetic acid and water solution. Sufficient sodium hydroxide is employed to react with the acetic acid to the point of exhaustion of the acid, forming sodium acetate, with an excess of lye remaining for saponification purposes. The solution is permitted to dissipate its heat generated by the interaction of sodium hydroxide and acetic acid until a substantially tepid temperature prevails.

The aciduous-oleaginous emulsion shown at 12 is mixed with the strongly alkaline solution represented at 17, as shown at 18. As is well known in soap making processes, the addition of an alkali metal to a fatty acid results in the saponification of the fatty acid. In the full-boiled process the saponification is carried on at elevated temperatures to obtain improved results and to avoid precise control of purity, proportion and agitation requirements. In the cold-made process, the saponification is successfully accomplished only with such precise temperature proportion, and purity control. In the cold-made process, agitation causes the emulsion to break and the entire soap batch is ruined. Preconditioned for saponification by the addition of dilute solutions of water soluble organic acids to the fatty acids and of a dilute solution of acetic acid to the alkali metal saponification is carried on without the precise control requirements conventionally known in cold-made processes. This preconditioning not only permits the agitation of the materials during saponification but in the soap of the present invention such agitation conducted in even a relatively violent manner is productive of improved results. The agitation of the fatty-acid-water-soluble-organic-acid emulsion and the acetic-acid-alkali-metal solution is represented at 18.

The violence and duration of the agitation performed at 18 are dependent upon the results desired. Normally the mixture is agitated in a mechanical beater for from three to five minutes and the vigor of agitation gradually decreased as the saponifying mixture approaches a homogeneous and finely textured condition. When the agitation is extended for longer periods the saponifying soap becomes crumbly and small quantities of liquor appear. Further, when the agitation is performed in the presence of the exothermic heat incident to saponification, a smooth fine soap mix results which upon cooling is a smooth, solid, hard soap. When the exothermic heat of saponification is permitted to dissipate preliminary to agitation until a sub-

stantially tepid condition prevails, a coarser grained crumbly soap results, somewhat similar to that achieved by extended periods of agitation. During the agitation step performed at 18, perfumes, filling materials, and/or other ingredients desired to be incorporated in the finished soap are added.

Subsequent to the agitation at 18, the saponified soap is permitted to cool as represented at 19. The soap resulting at 19 may be finished for commercial use as by cutting and pressing into bars, by grinding into powder or flakes, or by any other appropriate physical or other treatment desired. This finishing step is represented at 20. It has been found convenient when making a powdered soap, to conduct the agitation step 18 as described so as to achieve a crumbly soap. This crumbly soap is readily converted into soap powder by a simple crushing operation, thus inexpensively performing a powdering step conventionally of considerable expense. The crushing is preferably achieved by means of steel rollers between which the soap is forced but may be accomplished in any manner desired.

It is to be noted that soap produced by the processes described herein is of a quality having all of the attributes attributable to aging of conventional cold-made soap aged for several months promptly upon the completion of the saponification and cooling.

Where it is desired to remix the soap cooled at 19 as to add additional materials or to change the physical condition, the soap is heated slowly as represented at 21 until melted. Subsequent to melting the soap may be stirred, other materials mixed therewith, and generally treated as the soap was originally treated in the agitation step represented at 18. This step is schematically represented at 22 and is clearly distinguished from the conventional cold-made process in which such operations are not possible.

Subsequent to this second treating of the soap, the same is cooled and permitted to solidify at 23 as originally permitted at 19. This soap resulting at 23 is then finished in any desired manner as at 24. The finishing step 24 can take any of the forms suggested for step 20.

The following examples serve to illustrate various embodiments of the present invention. The examples are offered by way of explanation rather than limitation and it is to be understood that variations in quantities and substitutions of equivalent chemical materials may be accomplished without departing from the spirit or the scope of the present invention.

Example I

Coffee oil	kilograms	3.0
Commercial lye (94% sodium hydroxide)	grams	504
Water	liters	2.0
Acetic acid	grams	75
Oxalic acid	do	50

Example II

Animal fat	kilograms	3.0
Commercial lye (94% sodium hydroxide)	grams	515
Water	liters	2.0
Acetic acid	grams	50
Oxalic acid	do	75

5

Example III

Cotton seed oil	kilograms	3.0
Commercial lye (94% sodium hydroxide)	grams	564
Water	liters	2.0
Acetic acid	grams	100
Oxalic acid	do	100

Example IV

Coffee oil	kilograms	3.0
Commercial lye (94% sodium hydroxide)	grams	60
Water	do	2.0
Acetic acid	do	146
Oxalic acid	do	134

Example V

Peanut oil	kilograms	3.0
Commercial lye (94% sodium hydroxide)	grams	420
Water	liters	1.7
Sodium acetate	grams	150

Example VI

Olive oil	kilograms	3.0
Commercial lye (94% sodium hydroxide)	grams	420
Water	liters	1.5
Sodium acetate	grams	100
Sodium oxalate	do	50

Example VII

Corn oil	kilograms	3.0
Commercial lye (94% sodium hydroxide)	grams	420
Water	liters	2.0
Sodium acetate	grams	200
Sodium oxalate	do	100

Example VIII

Animal fat	kilograms	3.0
Commercial lye (94% sodium hydroxide)	grams	420
Water	liters	2.0
Sodium acetate	grams	200
Sodium oxalate	do	200

Example IX

Animal fat	kilograms	3.0
Commercial lye (94% sodium hydroxide)	grams	546
Water	liters	2.0
Oxalic acid	grams	134
Sodium acetate	do	200

Example X

Animal fat	kilograms	3.0
Water	grams	486
Commercial lye (94% sodium hydroxide)	do	100
Citric acid	liters	2

Example XI

Animal fat	kilograms	3.0
Water	liters	2
Commercial lye (94% sodium hydroxide)	grams	476
Tartaric acid	do	100

Example XII

Animal fat	kilograms	3.0
Water	liters	2
Commercial lye (94% sodium hydroxide)	grams	513
Oxalic acid	do	100

6

Example XIII

Animal fat	kilograms	3.0
Water	liters	2
Commercial lye (94% sodium hydroxide)	grams	490
Acetic acid	do	100

Example XIV

Animal fat	kilograms	3.0
Water	liters	2
Commercial lye (94% sodium hydroxide)	grams	475
Hydroxy acetic acid	do	100

Example XV

Animal fat	kilograms	3.0
Water	liters	2
Commercial lye (94% sodium hydroxide)	grams	478
Propionic acid	do	100

Example XVI

Animal fat	kilograms	3.0
Water	liters	2
Commercial lye (94% sodium hydroxide)	grams	476
Lactic acid	do	100

In the first four examples the sodium hydroxide is dissolved in a dilute solution of acetic acid in water, and the fatty acid suspended in emulsion form in a solution of the oxalic acid and water preliminary to the saponification step. It is to be understood that various oils and fats have various acidity characteristics and thus the proportions of alkali metal required to neutralize the same will vary somewhat. As is indicated in Examples 1 to 4 inclusively, various quantities of acetic acid and oxalic acid may be employed. Although there is no precise critical limit to the quantity of water soluble organic acid employed, it is generally preferable to have the content between one percent (1%) and eight percent (8%) by weight of the soap. Examples 1 to 4 inclusively also demonstrate the balancing of the alkali metal employed with the quantity of fatty acid, oxalic acid, and acetic acid to achieve a neutral soap, which in most instances is desired.

As previously described, the alkali metal in excess of that required by the acetic acid combines with the water soluble organic acid to form the alkali metal salt of said metal and acid. It has been discovered that the reduction of the alkali metal employed and the substitution of the alkali metal salt of the water soluble organic acid in the fatty acid emulsion in place of the acid itself will achieve comparable results. In Example 5, the peanut oil is suspended in emulsion form in a dilute solution of sodium acetate preliminary to the saponification by the sodium hydroxide. It is to be noted that in Example 5, no acetic acid is used with the sodium hydroxide. This achieves a result superior to that of the conventional cold-made process for making soap but not as good results as the preferred interaction of the alkali metal in a solution containing a salt of acetic acid and the alkali metal on the fatty acids in emulsion form.

In Example 6 the sodium hydroxide is dissolved in a dilute solution of sodium acetate and the olive oil suspended in emulsion form in a dilute solution of sodium oxalate preliminary to the saponification. Example 6 achieves results superior to Example 5 and that are comparable to the results of Examples 1 to 4 inclusively. Ex-

amples 7 and 8 demonstrate the use in various proportions of the alkali metal in solution in an aqueous sodium acetate solution and the emulsifying of the fatty acids while in a dilute solution of sodium oxalate.

Example 9 demonstrates the process of the present invention in a form in which sodium hydroxide is dissolved in a dilute aqueous solution of sodium acetate and the fatty acids emulsified in a dilute solution of oxalic acid preliminary to saponification.

Aqueous solutions of acetic acid and water soluble alkali metal salts of acetic acid are most successful as the medium in which the alkali metal may be dissolved preliminary to saponification. However, it is readily demonstrated that other water soluble organic acids and their water soluble alkali metal salts may be used in forming the fatty acid emulsions. Examples 10 to 16, both inclusively, demonstrate embodiments of the present invention in which the fatty acids are suspended in dilute solutions of various suitable water soluble organic acids preliminary to saponification. In these examples, the significant step of dissolving the alkali metal in a dilute solution of acetic acid or alkali metal salts of acetic acid has been omitted for purposes of simplicity. In this particular, the soaps resulting from Examples 10 to 16 are not preferred but demonstrate soaps involving certain phases of the present invention having advantages over conventional soaps.

It is obvious that the present invention is not limited to the use of sodium hydroxide as the alkali metal. For example, if potassium hydroxide is employed in place of the sodium hydroxide in Examples 10 to 16, both inclusively, highly satisfactory soaps are obtained. In order to make such soaps, the following quantities of potassium hydroxide are substituted for the specified quantities of sodium hydroxide:

Example	Grams of Potassium Hydroxide for Specified Sodium Hydroxide
10	680
11	667
12	718
13	685
14	665
15	668
16	654

The broad essence of the present invention is believed to reside in the discoveries that the emulsifying of the fatty acid employed in making soap in a dilute solution of organic acid or an alkali metal salt of an organic acid achieves the saponification advantages indicated above, that the conducting of the saponification step with the alkali metal dissolved in an aqueous solution of acetic acid or alkali metal salt of acetic acid is advantageous; and that the employment of these two discoveries in the saponification step permits the vigorous agitation of the materials during saponification achieving a resultant soap having physical properties contributing advantages to the soap not heretofore known in addition to outstanding chemical advantages incident to its composition.

In Fig. 2 is schematically represented in greatly magnified form, the physical condition of soap produced by the process of the present invention. Hard, alkali metal soap particles are in-

dicated at 27. The particles are sheathed by thin layers of water soluble salts of the organic acids and the alkali metal employed, represented at 28. These layers of soluble salts act much in the manner of mortar in holding the soap particles 27 in bar or flake form. The soap particles are not necessarily spherical and may take various shapes. They are small in size, somewhat dependent upon the agitation conditions as to temperature and violence thereof prevailing during saponification. When the agitation is not unduly long and the agitation is conducted before the exothermic heat of saponification has been dissipated, the particles formed are microscopic in size. When the agitation is conducted for protracted periods and/or at reduced temperatures the particles are somewhat larger, approaching macroscopic in size. This is particularly true where the melting and re-agitating steps are employed.

As previously suggested, the soap of the present invention when agitated under conditions forming relatively large soap particles, may be powdered by a crushing operation. This crushing merely breaks the particles from each other where they have been joined by the salt layers 28. In use the water soluble salt films 28 are readily dissolved releasing the very fine particles of soap for prompt and effective action. To this phenomena are attributed many of the superior characteristics of the soap of the present invention relating to speed of sudsing, rate of cleaning, and the like. The soap is mild and gentle to the skin, delicate fabrics, hair and other materials easily damaged by conventional soaps. To what these gentle characteristics may be attributed is not definitely known, but it is thought that they may be incident to the sodium oxalate or other water soluble salt of the alkali metal in the resultant soap.

The process of the present invention obviates requirements for expensive, elaborate, and complex apparatus conventionally required for the production of high quality soap thus enabling small producers with limited capital to compete with large manufacturers. Upon the completion of the cooling of the soap after saponification, no further aging is required, the soap at that time possessing the attributes of cold-made soap that has been permitted to age for several months.

The process further obviates the precise temperature, proportion, and concentration requirements heretofore demanded in cold-made processes. Incomplete saponification is completely eliminated and thus this source of waste avoided. Scraps of soap normally considered waste may be reworked as described in connection with operations 21, 22, and 23 in Fig. 1 and completely utilized. The improvements of the process of the present invention enable the introduction of perfumes and other materials into soaps made with the simplicity of conventional cold-made processes without the danger of the separation of the emulsion during the addition of such materials.

Although I have herein shown and described my invention in what I have conceived to be the most practical and preferred embodiments, it is recognized that departures may be made therefrom within the scope of my invention, which is not to be limited to the details disclosed herein, but is to be accorded the full scope of the claims so as to embrace any and all equivalent processes and compositions.

Having described my invention, what I claim is new and desire to secure by Letters Patent is:

1. A process for making soap comprising forming an emulsion of oleaginous material in a water soluble organic acid, dissolving sodium hydroxide in a dilute solution of acetic acid to the exhaustion of the acetic acid with an excess of sodium hydroxide, reacting the excess sodium hydroxide in the solution on the oleaginous material in the emulsion to saponify the same and on the water soluble organic acid to form a sodium salt of the organic acid, and agitating the solution and emulsion during the saponification of the oleaginous material, said sodium hydroxide being employed in an amount sufficient to interact with the acetic acid, the weak organic acid of the emulsion, and with the oleaginous material to the substantial exhaustion of said materials.

2. In the cold-made process of manufacturing soap including the saponification of a fatty acid with an alkali metal hydroxide, a step directed to the preconditioning of the materials employed in said process for saponification comprising the formation of an emulsion of the fatty acid in an aqueous solution of a weak organic acid of low molecular weight preliminary to the saponification of the fatty acid by the alkaline metal hydroxide.

3. In the cold-made process of manufacturing soap including the saponification of a fatty acid with an alkali metal hydroxide, the steps of preconditioning the materials employed in the process for agitation during saponification, comprising the formation of an emulsion of the fatty acid in a dilute solution of a weak organic acid of low molecular weight in water, and the dissolving of the alkaline metal hydroxide in a dilute solution of acetic acid in water preliminary to mixing of the solution and emulsion for saponification.

4. In a process for making soap including the saponification of a fatty acid soap stock material with sodium hydroxide, the step of forming an emulsion of the soap stock material in a dilute aqueous acetic acid solution preliminary to saponification.
